MULTIPLE CONTAINER PACKAGE

Thomas M. Pace, Pensacola, Fla., assignor to St. Regis
Paper Company, New York, N.Y., a corporation of
New York

Filed May 19, 1965, Ser. No. 456,923
5 Claims. (Cl. 206—65)

This invention relates to a package, such as a paper-board carton in which is packaged a plurality of inner containers of a peculiar but heretofore well known shape, such as of the type disclosed in U.S. patent to Moore, granted February 8, 1944, No. 2,341,056, the containers being so arranged in the package as to be in a novel, firm, mutually-supporting, systematic arrangement requiring substantially a minimum amount of space.

The type of inner container referred to is formed of a short tubular section of paperboard or other sheet material having each end collapsed with abutting end edge portions brought into flatwise engagement and sealed together along a straight line forming a substantially linear seal perpendicular to the axis of the tubular section and with such straight line seal at one end of the container in a 90° angular relationship as compared with the like seal on the other end of the container. This type of container, which is very inexpensive and easy to construct, fill and seal, has come into extensive use for containing a variety of different types of powdered materials or liquids, but the container is of such an odd shape that the packing and arranging of a plurality thereof in a systematic way in any outer protective carton or box, presents a difficult problem, particularly if a group of same is to be packed in a square or rectangular carton of substantially minimum size and in such manner that they will remain securely in place. If such inner containers are placed in a carton in a random arrangement, protruding corner portions thereon will tend to become crushed against the carton walls or against each other, and in any event, the protruding corners will make necessary the provision of considerable wasted spaces in the carton.

The present invention provides a solution of these problems by way of so arranging a plurality of the containers with respect to each other and with respect to the carton walls, that the whole group may be fitted into the outlines of a square or rectangular carton (depending on the number and dimensions of the containers in the group) so that there will be a minimum of waste space in the carton and each of the containers will be in a predetermined position to press against the next container or containers and hold them securely in place, in positions such that none of the corners of the end closures thereof tends to protrude beyond the normal outlines of the rectangular carton.

In accordance with the invention, the containers of the above-mentioned type are so arranged side by side in the carton, that the linear end seals thereof contact one interior wall surface of the carton along spaced-apart parallel lines which run diagonally across the carton wall, whereas on the opposite ends of the same containers, the linear sealed ends similarly contact an opposite interior surface, also along diagonal lines, but along diagonals that are at 90° to the first-named container ends. This results in an arrangement whereby the middle side portion of one container at a location thereon which is somewhat rounded, engages crosswise a similar rounded midportion of the next adjacent container or containers.

Various further and more specific objects, features and advantages of the invention will appear from the description given below, taken in connection with the accompanying drawings, illustrating by way of example preferred forms of the invention.

2

In the drawings:

FIG. 1 is a perspective view of a single one of the inner containers of known type such as of the above-mentioned prior U.S. patent;

5 FIG. 2 is a perspective view showing a carton with its cover portions open and containing a plurality of the containers arranged and packed therein in accordance with the invention;

10 FIG. 3 is a horizontal sectional view taken substantially along the horizontal plane of line 3—3 of FIG. 2;

FIG. 4 is a view similar to FIG. 2, but illustrating the invention as applied to a carton adapted to contain two rows of the inner containers as shown therein; and

15 FIG. 5 is a vertical sectional view taken substantially along the vertical plane of line 5—5 of FIG. 4.

Referring now to the drawings in further detail, it will be noted that the type of known inner container which is to be packed in a carton or box in accordance with the invention may comprise a generally tubular short length section 10 formed of paperboard or other sheet material

20 one end of which is collapsed along a straight line 11 at the bottom of the container, and the other end of which is also collapsed along a straight line as at 12, here shown as being at the top of the container, the collapsed edges in each case being suitably sealed together by the use of suitable adhesives or heat sealing methods following

25 filling of the container with whatever product is to be packaged therein. More particularly, it will be noted that the straight line seal 11 is in a position at 90° to the straight line seal 12 at the other end of the container

30 related to the central axis thereof, as indicated by dotted line 13. Thus an odd shape is provided having four corners as at 14, 15, 16 and 17 with the consequence that if such containers are placed in a carton at random positions, there will be a great deal of waste space and such corners will protrude in random directions on the various containers, so that same will tend to protrude at irregular points against the surfaces of adjacent containers and against the interior wall surfaces of the carton, thereby giving rise to conditions causing deformation or puncturing of the containers during shipment or rough handling.

As shown in FIG. 2, a carton or box 17 is provided

35 formed of paperboard or other suitable material and, in the form here shown, such carton is rectangular in cross section in both its horizontal and vertical dimensions, though the invention is applicable to instances where the carton might be used which would be square or rectangular in one or more of its cross-sections, depending upon the dimensions of the inner containers to be contained therein and the number of the latter to be packaged.

Quite surprisingly, I found that the inner containers may be arranged in the carton in the manner shown in FIG. 2, thereby fully solving the problem of compactly packing such containers in a systematic way and so as to

40 present a neat and attractive appearance and with each container so positioned as firmly to retain the adjacent containers against displacement and in a firm mutually-supporting relation, with none of the corners protruding beyond the outlines of the carton interior.

45 That is, the containers 10 are so positioned that the straight line seals 11 at one end thereof will be positioned along spaced-apart parallel lines running diagonally across a carton wall such as at 18. The straight line seals 12 at the other ends of the containers will similarly be placed along spaced-apart lines extending diagonally across an opposed wall, as at 19, of the carton, but diagonal in directions at right angles to the container ends.

50 This results in an arrangement such that, as best shown in FIG. 3, bulging or rounded side portions as at 20 and 21 at the middle of adjacent cartons, will come into engagement, thereby placing the adjacent containers in a firm mutually-supporting relation such that they cannot become

55 separated. The containers 10 are so arranged that the straight line seal 11 at one end of each container will be positioned along spaced-apart parallel lines running diagonally across a carton wall such as at 18. The straight line seals 12 at the other ends of the containers will similarly be placed along spaced-apart lines extending diagonally across an opposed wall, as at 19, of the carton, but diagonal in directions at right angles to the container ends.

55 This results in an arrangement such that, as best shown in FIG. 3, bulging or rounded side portions as at 20 and 21 at the middle of adjacent cartons, will come into engagement, thereby placing the adjacent containers in a firm mutually-supporting relation such that they cannot become

60 separated. The containers 10 are so arranged that the straight line seal 11 at one end of each container will be positioned along spaced-apart parallel lines running diagonally across a carton wall such as at 18. The straight line seals 12 at the other ends of the containers will similarly be placed along spaced-apart lines extending diagonally across an opposed wall, as at 19, of the carton, but diagonal in directions at right angles to the container ends.

65 This results in an arrangement such that, as best shown in FIG. 3, bulging or rounded side portions as at 20 and 21 at the middle of adjacent cartons, will come into engagement, thereby placing the adjacent containers in a firm mutually-supporting relation such that they cannot become

placed upon jarring the package during shipment. This ⁵ result results from the fact that the straight line sealed ¹⁰ is of each container will be held in uniform contact ¹⁵ with the bottom walls ¹⁸ and ¹⁹ by the bulging middle wall portions as at ²⁰, ²¹. These bulging wall portions will contact each other in a crossed relationship and such that the ²⁰ relatively stiff corners and sealed end portions on each ²⁵ of the containers are in any event kept out of contact with adjacent container or containers at all times.

As further shown in FIG. 2, the carton may be provided with a cover, as at ²², having conventional side and front flaps, as at ²³, ²⁴, and ²⁵. It should be noted that when the cover is closed, it will come into contact with rounded diagonally-extending ridges as at ²⁶ along the bottom of the inner containers, and similar ridges along the bottom of each of the containers will be held in diagonal positions in contact with the bottom wall of the carton. This results in effect in locking all of the plurality of inner containers in their desired respective positions, each container uniformly contacting, along diagonals, both the front and rear walls of the carton, as well as the bottom and top walls. Furthermore, the sides of end containers of the plurality will engage the end walls of the carton along straight diagonal lines, one of which is indicated by the dotted line ²⁷ in FIG. 2. That along this diagonal line, a bulging side wall portion, at ²⁸ (see FIG. 3) will engage the end wall of the carton, and similarly, at the other end of the carton, a bulging container wall portion ²⁹ will come into engagement with and extend diagonally across the carton end ¹.

As shown in FIG. 4, two rows of the end containers are shown packed side by side in a single carton ³⁰, in this case, the sealed straight line ends ¹² of the containers are positioned along spaced-apart diagonal lines as to come into contact with a hinged cover portion ³¹ when the latter is swung to closed position. Also, in this arrangement, as best shown in FIG. 5, the straight line lower end seals ¹¹ of the containers are brought into contact with the bottom ³² of the carton. The arrangement of the front row of inner containers as shown in FIG. 4, is, of course, the same as that of FIG. 2, except that in FIG. 4 the straight line seals are brought into contact with the top and bottom walls of the carton instead of the front and rear walls, as in FIG. 2. The back row of inner containers is shown by dotted lines in FIG. 4, and as shown in section at the right-hand side of FIG. 5, is, of course, arranged the same as the front row, and this back row is designed to be covered by a cover portion ³³, which comes into contact with the upper straight line seals of the inner containers along spaced-apart diagonal lines, as shown by the dotted lines in the upper part of FIG. 4.

If desired, the front edge of the cover portion ³³ may be provided with a deeply-extending flap as at ³⁴, which, when down in closed position, forms a divider separating the front and rear rows of the inner containers and in preventing same from being displaced during movement. The ends of the cover ³³ may be provided with conventional flaps, one of which is shown at ³⁵, which may, if desired, when the cover is closed, be interlocked between layers of the end wall portions ³⁶ of the carton. The front cover ³¹ may be provided with suitable depending flaps as at ³⁷, ³⁸ and ³⁹, which when the cover portion is closed, may be slid down, as will readily be understood, into locations such as normally hold the cover closed.

As is best shown by FIG. 5, the middle bulging portions of the containers, as at ⁴⁰ and ⁴¹, will engage the side walls of the carton along diagonal lines, such as indicated by the dotted line ⁴² in FIG. 4. Also, bulging side portions as at ⁴³, ⁴⁴ will come into contact either with each other or with the intervening depending flap ³⁴

in a manner comparable to the way in which the bulging portions contact in crosswise relation, as indicated at ²⁰, ²¹ in FIG. 3.

It will be apparent that similar principles may be followed in packing any desired plurality of the inner containers in one, two or more rows, with a plurality in each row.

Although, upon inspection of various figures of the drawings, it might seem to be a simple matter to select or choose the container arrangement shown, yet even experienced packaging experts, upon emptying the containers from the cartons as shown, generally find it a perplexing and puzzling problem to replace them as there shown, and more particularly so if any considerable number of the containers are to be put into a single carton.

The term "rectangular carton" as used herein is intended to be applicable to cartons of which the vertical and horizontal cross-sections thereof may be either rectangular in the usual sense, or square. In the appended claims reference to the carton walls is intended to be applicable to the side walls as well as the top (cover) or bottom walls, as the case may be.

Although certain particular embodiments of the invention are herein disclosed for purposes of explanation, further modifications thereof, after study of this specification, will be apparent to those skilled in the art to which the invention pertains. Reference should accordingly be had to the appended claims in determining the scope of the invention.

30 What is claimed and desired to be secured by Letters Patent is:

1. A package with a plurality of inner containers each of which comprises a length of tubing of sheet material collapsed flatwise at each end and sealed along linear seals which are perpendicular to the axes of the containers, and the seals at opposite ends of each container being in positions extending in directions at right angles to each other, said package comprising in combination a generally rectangular carton containing at least one row formed of a plurality of said inner containers arranged side by side, the linear seals of one end of each of which engage a wall of the carton along spaced-apart parallel lines extending diagonally across such wall, the seals at the opposite ends extending in parallel spaced-apart diagonal relation with respect to and in a plane opposite to said wall, and each container having areas at its mid-portion which are rounded in cross-section and which engage in crossed relation with like rounded areas on the next container or containers.

2. A package in accordance with the foregoing claim 1 and in which said wall comprises the bottom of the carton and said plane opposite to said wall comprises the plane in which a cover for the carton is located.

3. A package in accordance with the foregoing claim 1 and in which said plane opposite to said wall comprises the plane in which is located the wall of the carton opposite to said first-named wall.

4. A package in accordance with the foregoing claim 1 and in which a plurality of said rows of inner containers are provided to extend side by side in the carton.

5. A package in accordance with the foregoing claim 4 and in which the carton is formed with separate hinged covers respectively for said rows, at least one of said covers having a depending flap separating one of said rows from another.
